ANTISLIP SHOE

Filed Aug. 16, 1929

FIG. 1

FIG. 2

FIG. 3

INVENTOR
MICHAEL GOLDENBERG

BY
AdCaesar
ATTORNEY

UNITED STATES PATENT OFFICE

MICHAEL GOLDENBERG, OF PHILADELPHIA, PENNSYLVANIA

ANTISLIP SHOE

Application filed August 16, 1929. Serial No. 386,369.

This invention relates to anti-slip devices for shoes and more particularly to anti-slip devices for athletic shoes and has for its general object the provision of an anti-slip device which will not accumulate dirt, mud, etc., herein generically called foreign substance.

There are many well known anti-slip devices used at the present day on athletic shoes. The type used depends on the sport. In baseball the well known "spike" shoe is in general use.

The "spike" now in general use consists of an iron or steel supporting member of a general triangular shape having a comparatively wide spike member at each of the vertices of the triangle. The inner portion of the bearing plate or supporting member is cut away for the purpose of lightening the structure.

20 It has been found that dirt, mud, etc. accumulates and cakes in this cut out portion. This has been found to be highly objectionable since among other things it adds additional weight thus serving to slow up the athletes. It is the applicant's particular purpose to provide a structure which will be free from the above mentioned objectionable features.

More particularly stated, one of the objects of my invention is to provide an anti-slip athletic shoe wherein the space in the anti-slip device available for the accumulation of mud is reduced to a minimum.

Another object of this invention is to provide an anti-slip athletic shoe of the spike type with a plate whereby the space in the anti-slip device available for the accumulation of mud is reduced to a minimum.

Another object of this invention is to provide an anti-slip device for an athletic shoe wherein the space available for the accumulation of mud and extraneous matter is reduced to a minimum.

Another object of this invention is to provide an anti-slip device of the spike type for an athletic shoe wherein the space previously available for the accumulation of mud and other foreign substances is eliminated.

These and other objects will become evident from the following detailed description

and the drawings which form a part thereof.

In the drawings Fig. 1 is a bottom view of the shoe with an anti-slipping device and my protective plate attached thereto.

Fig. 2 is a section taken along the line 2—2 of Fig. 1.

Fig. 3 is an enlarged section taken along the line 3—3 of Fig. 1.

Referring more particularly to the drawings wherein similar reference numerals denote similar parts reference numeral 1 designates the shoe and its anti-slipping device as a unit. The shoe 1 is made up of a sole 2, an upper 3, and anti-slipping members 4.

The anti-slipping members 4 are of the "spike" type and are composed of a base plate 5 and anti-slipping elements or spikes 7.

The base plate 5 has a hole 6 formed therein which is bounded by the arms 10 of the base plate 5. An aluminum dust plate 8 covers the hole 6 thus serving to close the same and prevent mud, dirt or foreign substance of any nature from accumulating in the hole 6.

The base plate 5 and the dust plate 8 are both attached to the shoe sole 2 by means of rivets 9.

The above disclosure is by the way of illustration only and not by the way of limitation since many obvious changes may be made without departing from the spirit of my invention. For instance, instead of an anti-slipping device of the type shown any other anti-slipping device having an aperture therein where dirt might accumulate may be used: Instead of an aluminum plate any other plate which has the necessary elements of strength and lightness may be used: Instead of attaching the dust plate to the anti-slipping device in the manner shown it may be attached in some other manner such as welding: Or the dust plate may be attached directly to the sole 2 of the shoe.

These as well as other changes are contemplated by me and, therefore, no limitations should be understood from the above disclosure. The appended claims should therefore be construed as broadly as possible in view of the prior art.

The term "closing" as used in the speci-

fication and claims is used to denote means which overlie the aperture but do not fill the same, thus effectually preventing any material from being inserted into the chamber formed by the said closing member and the other walls of the said aperture while at the same time permitting the existence of such a chamber.

Having described my invention what I claim as new and useful is:

- 10 1. The combination of a shoe, anti-slipping means having an opening formed therein carried by the said shoe, and means for closing the said opening in the said anti-slipping means whereby the accumulation of foreign substances in the said opening in the said anti-slipping means is obviated.
- 15 2. The combination of a shoe, a plurality of anti-slipping means each having an opening therein carried by the said shoe, and a metal plate associated with each said anti-slipping means for closing the said openings in the said anti-slipping means whereby the accumulation of foreign substances in the said openings in the said anti-slipping means is obviated.
- 20 3. The combination of a shoe; a plate having an opening therein carried by the said shoe; anti-slipping elements carried by the said plate; and a dust plate associated with the said first plate, the said dust plate covering the said opening in the said first plate whereby the accumulation of foreign substances in the said opening is obviated.
- 25 4. The combination of a shoe, a plate having an opening formed therein carried by the said shoe, anti-slipping means carried by the said plate, and a dust plate associated with the said first plate the said dust plate being of a material of specific gravity which is less than that of the first said plate and covering the said opening in the said plate whereby the accumulation of foreign substances in the said opening is obviated.
- 30 5. As an article of manufacture a shoe, a plurality of plates each plate having an opening formed therein, a plurality of anti-slipping elements carried by each said plate, a dust plate covering each said opening in each said plate, and fastening means extending through each said first plate and the dust plate whereby each said plate and dust plate are simultaneously attached to the said shoe.
- 35 6. The combination of a shoe; a plate having an opening therein carried by the said shoe; anti-slipping elements carried by the said plate; and a metal dust plate covering the said opening in the first said plate whereby the accumulation of foreign substances in the said opening is obviated.

In witness whereof I hereby affix my hand and seal:

MICHAEL GOLDENBERG.
